CLAIM

The ornamental design for a fluid storage bottle, as shown and described.

DESCRIPTION

FIG. 1 is a perspective view of a fluid storage bottle showing my new design;

FIG. 2 is a left side elevational view thereof;

FIG. 3 is a right side elevational view thereof;

FIG. 4 is a front view thereof;

FIG. 5 is a rear view thereof;

FIG. 6 is a top plan view thereof; and,

FIG. 7 is a bottom plan view thereof.

The broken lines represent portions of the structure that form no part of the claim.
